UNITED STATES PATENT OFFICE.

ERWIN J. JONES, OF ST. PAUL, MINNESOTA.

SNOW CONDENSER.

Application filed November 27, 1926. Serial No. 151,231.

My invention relates to a machine for removing snow from streets, roads, etc., and then condensing and disposing of it. The object is to provide an efficient snow cleaning device which scoops up the snow from the surface, subjects it to an initial reducing process comprising a series of steam jets and further condensing and handling means hereinafter described and as illustrated in the accompanying drawing, in which:

Fig. 1 is a top view of my device mounted on the front end of a steam traction engine.

Fig. 2 is a side elevation of the tractor shown in Fig. 1 and my device in section 15 about as on line 2—2 in Fig. 1.

Fig. 3 is an enlarged detail elevation of one of the snow-actuated plates of my device and its steam valve controlling means.

Fig. 4 is a sectional detail of the steam 20 valve in Fig. 3 and adjacent parts of the steam manifold about as on line 4—4 in Fig. 3.

Fig. 5 is a vertical longitudinal section of the main steam passage and branch pipes of 25 my steam distributor or manifold and a steam operated rotary motor for operating a water pump.

Fig. 6 is an enlarged sectional elevation 30 about as on line 6—6 in Fig. 5 and illustrating further automatic steam feeding means for the rotary pump motor.

Referring to the drawing by reference numerals I have illustrated my device mounted on the front end of a steam thresher engine 35 of which 10 designates front wheels, 11 the rear or traction wheels, 12 is the cab at the rear end of an elongated boiler 13 having a fire box 14. 15 is the usual smoke stack and 16 a steam dome on top of the boiler.

40 17 is an upright box-like frame preferably of sheet metal and opening forwardly, its rear wall designated as 17 being suitably secured to the front of the boiler 13 and adjacent parts and forward of the wheels 10 of the engine. 17^a is the top or roof of the housing, 17^b the side walls and 17^c the bottom of the housing.

On the rear wall 17 I secure an upright hollow steam manifold 18 communicating by 50 means of a pipe 19 with the interior of dome 16. Said manifold has a number of vertically spaced forwardly directed conductor pipes 18^a. At the front end of each conductor pipe 18^a it is connected with a transversely arranged horizontal upper pipe 20 of a quadrangular pipe frame of which 21 is

the other horizontal pipe, both pipes 20—21 connected at their adjacent ends by pipes 22 and each said pipe frame is normally in a forwardly and downwardly directed angular 60 plane from its pipe 18^a. Each of these pipe frames comprises a steam conductor, the horizontal pipes so arranged that the lower pipe 21 is in fixed parallel relation to the upper pipe 20 of the next lower pipe frame 65 but outwardly thereof and slightly higher (see Figs. 2 and 3).

Each pipe 21 is provided with a row of outlet apertures directed upwardly and rearwardly to provide steam jets directed 70 accordingly as indicated by arrow 23 in Fig. 3 and each pipe 20 has like outlets directed rearwardly and downwardly to provide steam jets directed as arrow 23^a toward the rear wall of the housing.

75 24 are a series of vertically spaced pivotally suspended plates each extending between the side walls 17^b and pivoted therein as at 25 and its lower edge normally resting on a pipe 21 (see Figs. 2 and 3) with the plate inclined rearwardly and downwardly from its pivoted edge.

26 is the main snow scoop and initial snow handling part of my device. It comprises a forwardly and downwardly inclined plate 80 secured to two vertical end plates 27 which are pivoted on a shaft or pin 28 retained in transversely registering apertures in the side walls 17^b and at the lower front part thereof. 29 is a primary fixed plate or scoop 90 mounted on said shaft 28 and inclined upwardly and rearwardly therefrom to the lowest pipe 21 in the housing (see Fig. 2). 29^a are secondary plates or scoops mounted between the side walls 17^b in spaced relation and parallel to scoop 29.

30 is a steam heated floor plate comprising 95 two plates with steam space between them and communicating with the interior of the lowest pipe 21, the plate sloping downwardly 100 and rearwardly to the lower part of wall 17. It is thus obvious that water accumulating on top of the plate 30 will flow rearwardly to wall 17 in which is provided an outlet 31 (Fig. 2) communicating with a centrifugal 105 pump 32 fixed on the lower part of wall 17 and which forces the water through a conduit 33 into a water reservoir 34 suitably attached to the under side of boiler 13. Said reservoir has a suitable water outlet 35.

110 The pump 32 rotates horizontally and is operated by a vertical drive shaft 36 the

upper end of which is driven by a suitable steam driven motor or small turbine 37 in a housing 38 fixed on the rear side of wall 17 and having a piston valve 39 communicating with the interior of the manifold 18. Said valve has a stem 39^A within the manifold and there pivotally connected with the lower end of a vertical lever arm 40 pivoted at 41 and the upper end of its upper arm carrying a circular plate valve 42 normally closing the steam passage between steam pipe 19 and the interior of the manifold (see Fig. 5). When steam is circulating through manifold 18 the plate 42 is pushed forward and the lever 40 pushes rod 39^A and valve 39 rearward and steam passes through into the turbine by way of a passage 38^A to rotate the turbine and operate the pump. Steam is exhausted from the turbine through an opening 43 in wall 17 and into the housing (see Figs. 5 and 6).

44 is a cylindrical valve in each manifold outlet pipe 18^A and normally closing the transverse steam passage in pipe 20 by being pressed forward against the end web 18^{A'} of pipe 18^A. 44^A is a piston rod extending forward and out of the pipe, its exposed end pivotally secured to a reciprocable connecting rod 45. The other or forward end 30 of said rod 45 is pivotally secured as at 46 to a plate 24. The passage of steam to any and all of the rectangular pipe frames is prevented as long as the piston 44 is in closing position (as in Fig. 3) and at a time 35 when the corresponding plate 24 is in resting position shown.

It will now be readily understood that when my device is in operation moving forward through snow, the pressure of snow 40 against one or more of the plates 24 will cause the latter to tilt rearwardly and upwardly such upward tilting causing each plate to move its connecting rod 45 rearwardly and its valve 44 is moved rearwardly in pipe 18^A thus permitting steam to circulate through the cylindrical valve into the pipe of the rectangular frame. A row of steam jets are immediately brought into action in pipe 21 and directed upwardly and 50 rearwardly through the snow passing under plate or gate 24. This steam immediately breaks up and melts the snow and blows it rearwardly in an inclined direction toward and under pipe 20. Said pipe 20 has the 55 downwardly and rearwardly directed apertures through which more steam is immediately sprayed in a continuous sheet through the partly condensed snow blown rearwardly by pipe 21. The snow thus being subjected to two continuous sprays of steam directed through it at different angles, immediately reduces the snow to water which drops downwardly within housing 17 to the heated plate from whence it is 60 pumped into the water reservoir.

It is obvious that live steam is brought into direct action on the snow regardless of the depth of snow on the road. The higher the drifts of snow the more plates 24 are tilted back to let the snow enter the 70 housing as the latter moves forward and each tilting plate automatically opens the required steam jets for use to condense the snow.

The device may travel a considerable distance before the melted snow (water) will 75 completely fill the reservoir 34 and then the machine may be stopped to drain the reservoir into a sewer or ditch. Where the device is used on a railroad the device is mounted on the front end of a locomotive and suitable steam pipe connection (not shown) made. In the latter case the reservoir 34 is unnecessary as the water could be forced through a hose directed to deliver the water a considerable distance from the track.

I claim:

1. In combination with a power driven vehicle having a source of steam, an upright housing mounted on the front end of said vehicle and open forwardly, a snow scoop mounted on the lower end of said housing and directed forwardly thereof, a primary scoop rearward of said main scoop, a series 90 of vertically spaced secondary scoops fixed transversely in the open end of said housing and plates hinged one under each of said latter scoops and extending normally down and rearwardly to close the space between 95 two adjacent scoops, a pipe frame fixed transversely of the housing rearward of each said scoop and communicating with the source of steam, steam outlets provided in the horizontal members of each said pipe frame, said main snow scoop adapted to move snow into the housing when the vehicle is propelled forwardly and the successive vertically arranged hinged plates adapted to be swung rearwardly by engagement of snow therewith according to the depth of snow, 100 a steam valve for each said plate and adapted to be opened by the swinging movement of the plate to let out steam through said apertures, the said apertures being arranged 105 to spray steam through the snow upwardly and downwardly in rearward angular direction to melt the snow, said valves being normally closed when the plates are in normally closed and suspended position, and means 110 for receiving and storing said melted snow.

2. The structure specified in claim 1 in which said latter means comprise an outlet pipe from the lower part of said housing, a reservoir carried by said vehicle and said pipe communicating with said reservoir, and a pump for forcing said melted snow to the reservoir.

3. The structure specified in claim 1 in which said latter means comprise an outlet 130

pipe from the lower part of said housing, a reservoir carried by said vehicle and said pipe communicating with said reservoir, and a pump for forcing said melted snow to the 5 reservoir; a steam distributing manifold in said housing, a conductor pipe from said manifold to each said steam sprayer frame, a main feed pipe from the source of steam to said manifold and an automatic valve device 10 within said manifold to control passage of steam to said pump.

4. The structure specified in claim 1 in which said latter means comprise an outlet pipe from the lower part of said housing, 15 a reservoir carried by said vehicle and said pipe communicating with said reservoir, and a pump for forcing said melted snow to the reservoir; a steam distributing manifold in said housing, a conductor pipe from said 20 manifold to each said steam sprayer frame,

a main feed pipe from the source of steam to said manifold and an automatic valve device within said manifold to control passage of steam to said pump, said automatic means comprising a vertical beam lever, said manifold having a steam outlet communicating with the pump and adjacent the lower end of said beam lever, a disc valve fixed to the upper end of said beam lever and normally closing the feed pipe, said disc valve adapted to be moved horizontally from its normal position when steam is released at any of said steam spraying frames and tilt the beam lever; a valve in said lower outlet of the manifold and operable by said tilting movement of the beam lever to admit steam to the pump for the purpose set forth. 25 30 35

In testimony whereof I affix my signature.

ERWIN J. JONES.
